DESIGN FOR A COMBINATION RADIO AND PHONOGRAPH CABINET OR THE LIKE

Roy M. Alamon, Wichita Falls, Tex.

Application October 4, 1947, Serial No. 141,758

Term of patent 7 years

(Cl. D56—4)

To all whom it may concern:

Be it known that I, Roy M. Alamon, a citizen of the United States of America, residing at Wichita Falls, in the county of Wichita and State of Texas, have invented a new, original, and ornamental Design for Combination Radio and Phonograph Cabinet or the like, of which the following is a specification, reference being had to the accompanying drawings, forming a part thereof.

In the accompanying drawings:

Fig. 1 is a perspective view of the combination radio and phonograph cabinet, showing the front, an end and the top thereof;

Fig. 2 is a similar view thereof, but on a reduced scale and showing the opposite end of the cabinet.

The rear of the device is substantially plain and unornamented.

I claim:

The ornamental design for combination radio and phonograph cabinet or the like, substantially as shown and described.

ROY M. ALAMON.
